(57) **CLAIM**

The ornamental design for a deck slat, as shown and described.

DESCRIPTION

FIG. 1 is a perspective view of a deck slat showing our new design;

FIG. 2 is a top plan view thereof;

FIG. 3 is a front elevational view thereof;

FIG. 4 is a bottom plan view thereof;

FIG. 5 is a left side elevational view thereof; and,

FIG. 6 is a right side elevational view.

The broken lines shown in the drawing figures are for illustrative purposes only and form no part of the claimed design.

The deck slat has been broken on one end to indicate indefinite length.
